[57] ABSTRACT

A plurality of sensors detect the passage of a sheet of copying paper through a copying machine. A plurality of storage circuits having set and reset states are associated with the sensors. Each sensor, on detecting the paper, sets its associated storage circuit and resets the preceding storage circuit. Timers actuate an alarm if any storage circuit remains set longer than a predetermined time and indicator lights show which storage circuit is set. In order to allow for variable exposure times, one of the storage circuits is set by detection of the paper at the exposure position and is reset by the start of the exposure. The next storage circuit is set by the termination of the exposure and reset by detection of the paper's leaving the exposure position. Thus the paper may remain at the exposure position for any length of time without producing an alarm as long as exposure is in process.

FIG. 6

PAPER FEED STOPPAGE DETECTION MEANS IN AN ELECTRONIC PHOTOCOPYING MACHINE

BACKGROUND OF THE INVENTION

1. Field of the Invention

The present invention relates to a means for the detection of stoppage of copy-paper feed in an electronic photocopying machine, and more particularly to an improved stoppage detection means, which not only accurately detects stoppages of paper feed, but also indicates the locations thereof in a photocopying machine.

2. Description of the Prior Art

In a photocopying machine, the photo-image of an original document to be copied is transferred to sheets of copy-paper, which move through the machine. The main stages of the process are feeding sheets of copy-paper from a hopper, exposure thereof to an image of an original document to be copied, development of the image, and fixing and delivery of the sheets to a delivery tray. The different stages of the process are effected in different parts of the photocopying machine, and normally, sheets of copy-paper are fed, one at a time, through the different stages by rollers, or similar means. A problem that can arise in the photocopying machine is that of stoppage of the feed of copy-paper sheets in some internal part of the machine. Conventionally, it has been known to provide a sheet detection element associated with a timer, as a means for the detection of such stoppages. The detection element is provided at the outlet of the photocopying machine, that is at the point of delivery into the delivery tray, and the timer is set to give a warning if a sheet of copy-paper is not detected by the detection element a certain time after being fed into the photocopying machine from a hopper. The set time, after which the timer is to give a warning, is generally slightly longer than the time calculated to be necessary for sheet of copy-paper to travel from a hopper, through all the photocopying stages in a photocopying machine, and to a delivery tray. Such conventional means are simple, but have the disadvantage that when multiple copies of a document are required, and successive sheets of copy-paper are fed from a hopper, the sheets pass through the different stages and appear at the delivery tray at different intervals of time, and it is therefore necessary to employ two different timers, or to make the set time, after which a stoppage warning is to be given, slightly longer than the longest time anticipated to be required for completing one photocopying process. But in this case, considerable time may elapse between the actual occurrence of a stoppage and a warning thereof being given. Another disadvantage of such conventional stoppage detection means is that there is merely an indication that a stoppage in the feed of copy paper has occurred, and there is no indication of the location of the stoppage.

Although this problem can be resolved by a plurality of detectors located on the path of copy-paper through a photocopying machine, this has the disadvantage of making construction complicated.

Also, the times required for different stages in a photocopying process are not always the same. For example, in machines, in which photocopies are produced by exposing sheets of copy-paper to an image of an original document to form an electrostatic image thereon, adjustment of exposure is effected by varying the exposure time. In conventional means for detecting whether or not sheets of copy-paper are being fed at regular in-

tervals through a photocopying machine, allowance for such variations of the intervals required at different stages must be made by compensating the set time of a stoppage detector, or by increasing the set time sufficiently to allow for the longest variation that may be required. But in this case also, it is obvious that there may be a considerable delay in the response of the detection means, and for machines into which sheets of copy-paper are fed manually, such conventional detection means are completely inapplicable.

SUMMARY OF THE INVENTION

It is accordingly an object of the present invention to provide an improved paper feed stoppage detection means which overcomes the defects inherent in conventional detection means.

It is another object of the present invention to provide an improved paper feed stoppage detection means which comprises a plurality of detectors located at various points on the path of travel of sheets of copy-paper through an electronic photocopying machine, whereby rapid indication is provided of both the occurrences and of the locations of stoppages of the feed of sheets of copy-paper.

It is a further object of the invention to provide a simple, and easily manufactured stoppage detection means, in which signals from detectors are transferred to indicating means and to warning means by a single structure comprising a number of identical cascade-connected control circuits.

According to the present invention, one of the most important features resides in the provision of a paper feed stoppage detection means comprising a plurality of detectors provided on the feed path of sheets of paper, said detectors emitting output signals upon the detection of sheets of paper, a plurality of storage circuits, each of which produces output signals when set, and produces no output signals when reset, a 1st storage circuit being set by an input signal supplied thereto at the start of feed sheets of paper, and being reset by the first detector when a sheet of paper on said feed path reaches the first detector each subsequent storage circuit being set by one said detector and being reset by the succeeding detector on said feed path, a plurality of timers, each of which is actuated by one corresponding said storage circuit, and each of which produces an output signal if actuated longer than a certain time, and an alarm device actuated by an input signal from any one of said timers.

BRIEF DESCRIPTION OF THE DRAWINGS

These and other objects and features of the present invention will become apparent from the following description made, by way of example, in conjunction with preferred embodiments thereof with reference to the attached drawings, in which;

FIG. 1 is an electrical circuit block diagram of a paper feed stoppage detection means employed in an electronic photocopying machine according to one preferred embodiment of the present invention,

FIG. 2 is a cross-sectional view of the electronic photocopying machine provided with the paper feed stoppage detection means of FIG. 1, similar to FIG. 1, showing a portion of a paper feed stoppage detection means according to another embodiment of the present invention,

FIG. 4 is an electric circuit diagram applied to the paper feed stoppage detection means of FIG. 1 as a further embodiment of the present invention, and

FIGS. 5 and 6 are respectively electric circuit diagrams similar to FIG. 4, showing a portion of a paper feed stoppage detection means according to other embodiments of the present invention.

DESCRIPTION OF THE PREFERRED EMBODIMENTS

Before the description of the present invention proceeds, it is to be noted that, for the sake of brevity, like parts are designated by like reference numerals throughout the several views of the accompanying drawings. It is also to be noted that the concept of the present invention as well as its paper feed stoppage detection means herein disclosed as preferred embodiments can be applied in any field of industry other than the electronic photocopying industry, for example, in connection with metallic foil, synthetic film, cloth or other like sheet materials if such article is arranged as herein disclosed.

FIG. 2 shows the concrete construction of the electronic photocopying machine employing the paper feed detecting means showing in FIG. 1. Referring first to FIG. 2, the housing structure 101 is of a box-like shape having an upper glass plate 102 upon which an original document to be copied is placed and a hopper 103 to store sheets of copy-paper with a means including rollers 104 for feeding a sheet of copy-paper from the hopper 103 to the succeeding stages of process in a conventional known manner. In the housing structure 101 there is provided an exposure chamber 105 in which an image of the original document on the upper glass plate is exposed on the sheet of copy-paper fed from the feeding means through an optical means including lenses 106. Adjustment of exposure is effected by varying the exposure time. A developing chamber 107, in which the exposed sheet of copy-paper is developed to distinguish and to fix the image thereon by means of developing liquid for a certain period, and a drying chamber 108, in which the sheet of copy-paper developed is dried by means of heater 109, are also provided in the housing. The sheet of copy-paper having the image of the original document after passing through all the chambers is automatically led to and obtained on a delivery tray 110 provided at the lower portion of the housing structure 101.

Referring now to FIG. 1, a plurality of detectors 1, 2, 3, 4, 5 and 6 (detectors 3, 4 not shown), are provided and comprise micro-switches, photo-relays, or other elements, as described in further detail below. The detectors 1 . . . 6 are for the purpose of detecting the passage, through an electronic photocopying machine, of sheets of paper used for the reproduction of original documents, and are disposed at various locations in the photocopying machine. As shown in FIG. 2, the detector 1 is located at the outlet of the hopper 103, the detector 2 at the entry to the exposure chamber 105, the detector 3 at the outlet of the exposure chamber 105, the detector 4 at the outlet of the development section 107, the detector 5 at the outlet of the drying section 108, and the detector 6 at the outlet of the photocopying machine, leading to the delivery tray 110. Each detector 1 . . . 6 produces output signals when a sheet of paper passes the location of the detector. That is, detector 1 produces output signals when a sheet of paper

is fed into the photocopying machine from the hopper 103, detector 2 produces output signals when a sheet passes into the exposure chamber 105, detector 3 produces output signals when a sheet passes into the exposure chamber 105, detector 4 produces output signals when a sheet passes into the developing section 107, detector 5 produces output signals when a sheet passes into the drying section 108, and detector 6 produces output signals when a sheet is obtained into the delivery tray 110.

Needless to say, according to the invention, it is not essential that detectors be provided only in the above-described locations, but detectors may be provided at any locations where important steps of the photocopying process take place, or where a stoppage in the travel of sheets is anticipated.

Associated with, and connected to the detectors 1, 2, 3, 4, 5 and 6 are provided storage circuits 11, 12, 13, 14, 15 and 16, respectively (storage circuits 13, 14, 15 not shown). Each storage circuit 11 . . . 16 comprises, for example a flip-flop having two stable states 1 and 0 of conventional type, and has a set input terminal IS, a reset input terminal IR, and output terminals 0. When a storage circuit 11, 12 . . . 15, or 16 receives a 1, input at its set input terminal IS, it stores 1, and also produces a 1 output at each output terminal 0. A 1 input to the reset input terminal IR of a storage circuit resets the circuit, and, in this case, the circuit's output goes to 0.

Input to the set input terminal IS of the storage circuit 11 is supplied in the form of a signal which is emitted from a feeding circuit F when sheets start being fed from the hopper of the photocopying machine. Input to the reset input terminal IR of circuit 11 is supplied by the detector 1, when a sheet reaches the location of the detector 1, and is detected thereby.

Input to the set input terminal IS of the other storage circuits 12, 13, 14, 15 and 16 is supplied by the detectors 1, 2, 3, 4 and 5, respectively, and in that order, when the detectors 1 . . . 5 detect sheets of paper passing their various locations. Input signals to the reset input terminals IR of the storage circuits 12, 13, 14, 15 and 16 are supplied in the form of sheet detection signals from the detectors 2, 3, 4, 5 and 6, respectively, and in that order, when the detectors 2 . . . 6 detect sheets of paper passing their various locations.

Outputs from the storage circuits 11, 12, . . . 16 are supplied to, and actuate pilot lamps 21, 22, . . . 26 and timers 31, 32, . . . 36. That is, the storage circuit 11 supplies an input signal to pilot lamp 21, and also to timer 31, and so on. The pilot lamps 21 . . . 26 are provided in any convenient, visible location, for example, on the operating panel of the photocopying machine, and light-up when receiving input signals from the corresponding storage circuits 11 . . . 16. Therefore, when sheets are being fed through the photocopying machine, from the hopper to the delivery tray, normally, the lamps 21 . . . 26 are turned on, and then off, in turn. Also, of course, since the lamps 21 . . . 26 are lit in response to a starting signal, or signals from the detectors 1 . . . 5, each lamp 21 . . . 26 gives an indication of the location of a sheet of copy-paper.

Each timer 31 . . . 36 is actuated by input from an 0 terminal of the corresponding storage circuit 11 . . . 16, as stated earlier, and if this input does not cease before a set time T_i , which is adjustable for each timer, the timer sends a signal to an OR gate 40. Upon receipt of an input signal from any of the timers 31 . . . 36, the OR

gate actuates a device to give a warning that the normal time required for a sheet of copy-paper to travel between two detectors has been exceeded, in other words, that there is a stoppage.

The set time T_1 for each timer 31 . . . 36 is the time required for a sheet of copy-paper to travel from one detector to the next, and is given by the formula;

$$T_i = \frac{l_i}{S_i} + a_i \quad (1)$$

in which, l_i is the distance from a detector i to the next ($i+1$), S_i is the speed of travel of a sheet of paper from detector ($i+1$), and a_i is a time allowance.

For photocopying stages in which a sheet of paper remains stationary between the locations of two detectors for a certain time, this interval also is included in the set time for the corresponding timer. For example during exposure, sheets of copy-paper must remain stationary for a certain time in the exposure chamber, and the time $T'23$ required for a sheet of paper to travel from detector 2 to detector 3 is given by the formula;

$$T'23 = \frac{l_{23}}{S_{23}} + t \quad (2)$$

in which l_{23} is the distance between detectors 2, 3, S_{23} is the speed of travel of a sheet of paper between detectors 2, 3, and t is exposure time. The time set for timer 33 is thus

$$T_{23} = T'23 + a_{23} \dots \quad (3)$$

This value is generally suitable for photocopying machines in which exposure time is comparatively short. But in the case of machines in which a longer exposure time is required, in order to improve response, it is preferable to temporarily suspend the operation of timer 33 while exposure of a sheet is in progress, and to make the set time;

$$T_{23} + \frac{l_{23}}{S_{23}} + a_{23} \quad (4)$$

A description of the operation of the above-described equipment is given hereinbelow.

The photocopying process is started by actuation of a push-button switch (not shown) in the feeding circuit F, which causes paper to be fed from the hopper, and at the same time supplies an input to the set input terminal IS of the storage circuit 11. The storage circuit 11, now being set, produces 1 outputs at its output terminals 0. Output from one output terminal 0 of the storage circuit 11 causes the pilot lamp 21 to light up, thus giving an indication that a sheet of paper has entered the photocopying machine from the hopper and is travelling towards the location of the detector 1. Output from the other output terminal 0 of the storage circuit 11 actuates the timer 31. The set time for the timer 31 is slightly longer than the time calculated to be required for a sheet of paper to travel from the hopper outlet to the detector 1. If, therefore, the photocopying machine is functioning normally, the sheet of copy-paper reaches the detector 1 before the set time of the

timer 31 elapses. Upon detection of the sheet of paper, the detector 1 supplies a reset input to the input terminal IR of the storage circuit 11. This resets the storage circuit 11, and output at both the output terminals 0 thereof goes to zero, thus turning off the pilot lamp 21, and stopping the timer 31. The detector 1 simultaneously supplies a set input to the storage circuit 12. The storage circuit 12, being set, supplies an output which actuates the timer 32, and an output which turns on the pilot lamp 22, thus giving an indication that the sheet of copy-paper is travelling between detectors 1 and 2.

When the photocopying machine is functioning normally, the above-described operation is repeated as the sheet (or sheets) of copy-paper comes to the locations of the different detectors. Successive storage circuits 13, 14, 15 and 16 are set and reset by detection signals from successive detectors 2, 3, 4 and 5, and the pilot lamps 23, 24 . . . 26 are turned on and turned off, in turn. When the sheet of paper reaches the outlet of the photocopying machine, the detector 6 resets the storage circuit 16. All the storage circuits 11-16 are therefore now reset, all the pilot lamps 21-26 and timers 31-36 are off, and this completes one photocopying cycle. During this cycle of normal operation, all the timers 31-36 are stopped before their various set times elapse, and so no signals are supplied to the OR gate 40, and there is no actuation of a stoppage warning device.

The description of the operation of the means of the invention will proceed hereinbelow, by way of example, with reference to the case in which a sheet of copy-paper is blocked between the hopper outlet and the entry of the exposure chamber, that is between detector 1 and detector 2.

In this case, the pilot lamp 21 and timer 31 are switched on and then off, as described before. Also, the pilot lamp 22 and timer 32 are switched on by the storage circuit 12, which is actuated by a set input from the detector 1. Since, however, the sheet of paper being blocked before or in the exposure chamber does not reach the detector 2, there is no output from the detector 2, and no reset input to the storage circuit 12. The storage circuit 12 continues to supply output signals, the pilot lamp 22 remains on, and operation of the timer 32 continues. When the set time of the timer 32 elapses, the timer 32 supplies an input signal to the OR gate 40, and the OR gate 40 actuates a warning device. When the warning device is actuated, the pilot lamp is still on, and so it may be immediately determined that a sheet of copy-paper is blocked between the hopper outlet and the entry to the exposure chamber.

Similarly, if there is a stoppage in any other part of the photo-copying machine, a warning is given, and at the same time a particular pilot lamp is on, and gives an immediate indication of the location of the stoppage.

Referring now to FIG. 3, there is shown a block diagram of a 2nd embodiment of the present invention. In this 2nd embodiment, the circuits associated with the detectors 2, 3, at the entry and outlet of the exposure chamber, are divided into two blocks. One block B_1 comprises a storage circuit 13a, pilot lamp 23a, and timer 33a. The other block B_2 comprises a storage circuit 13b, pilot lamp 23b, and timer 33b. The storage circuits 13a, 13b actuate their respective pilot lamps 23a, 23b and timers 33a, 33b in the same manner as the

storage circuits described above, and the timers 33a, 33b supply input signals to the OR gate 40 if they are actuated continuously for longer than certain set times.

The storage circuit 13a is set by a set input from the detector 2, and is reset by an input signal which is supplied thereto from a start switch S₁ of a exposure circuit E when a sheet of paper, after passing the detector 2, reaches and stops at the exposure position, and exposure thereof commences. The storage circuit 13b is set by an input signal supplied thereto from a end switch S₂ of the exposure circuit E when exposure of the sheet has finished, and is reset by a reset input from the detector 3. In other words, the pilot lamp 23a and timer 33a are actuated from the time a sheet of copy-paper passes the detector 2 to the time the sheet reaches the position at which exposure thereof is to be effected. The pilot lamp 23b and timer 33b are actuated from the time the sheet leaves the exposure position to the time the sheet reaches the detector 3. During exposure of the sheet the lamps 23a, 23b and timers 33a, 33b are all off.

The set times T33a' of the timer 33a and T 33b' of the timer 33b are as follows:

$$TX' = \frac{l_{23}'}{S_{23}'} + a_{23}'$$

$$T33b' = \frac{l_{33}'}{S_{33}'} + a_{33}'$$

in which l₂₃' is the distance between detector 2 and the exposure position, S₂₃' is the speed of travel of a sheet of paper between the detector 2 and the exposure position, l₃₃' is the distance between the exposure position and the detector 3, S₃₃' is the speed of travel of a sheet of paper between the exposure position and the detector 3, and a₂₃', a₃₃' are time allowances.

This 2nd embodiment of the invention offers the advantage that even if exposure time is variable, the set times for the timers 33a, 33b may be fixed.

In FIG. 4, there is shown an example of circuit assembly of the timer and pilot lamp circuits associated with the storage circuits shown in FIGS. 1, 3.

The push-button switch, and each detector which actuates a changeover switch, SW_{S1}, SW_{a1} . . . SW_{a6}, are inserted in each circuit block L₁, L₂ . . . L₆ associated with successive pilot lamps and timers. These circuit blocks L are identical, and the description will proceed in reference to the operation of the circuit block L₁ associated with the pilot lamp 21, which is shown surrounded by a chain dot line in FIG. 4.

One terminal of the changeover switch SW_{S1} connects to a capacitor C_{b1}. The other terminal thereof normally connects to a resistor R_{a1} in parallel to the capacitor C_{b1}, and moves to a terminal connecting one side of the lamp 21 through a resistor R_{b1} when the switch SW_{S1} is actuated by a start signal of the push-button switch. The other side of the capacitor C_{b1} is connected to the gate terminal of a thyristor SCR1, which is in series with the lamp 21. The lamp 21 is on the anode side of the thyristor SCR1 through a resistor R_{c1}. The cathode side of a diode D_{b1} is connected to a point between the thyristor SCR1 and lamp 21, the diode D_{b1} thus being in parallel to the lamp 21. The anode side of the diode D_{b1} is connected to the base of an NPN transistor Ta1. A variable resistor VR_{a1} is provided in series with the collector circuit of the trans-

sistor Ta1 through a resistor R_{d1}. The collector of the transistor Ta1 also is connected through a resistor R_{e1} to the anode side of a diode D_{a1}, and to a capacitor C_{c1} in series therewith. The emitter of the transistor Ta1 is connected, through a resistor R_{f1}, to the capacitor C_{b1}. The cathode side of the diode D_{a1} is connected to an output terminal O1 which is connected to the timer 32. The anode side of the thyristor SCR1 also is connected to a capacitor C_{a1}, which is connected in series to the anode side of a diode D_{c1}, and to a resistor R_{h1} in parallel to the diode D_{c1}. On their other sides, the diode D_{c1} and resistor R_{h1} are connected in series to a capacitor C_{a2}, which forms part of the circuit block associated with the pilot lamp 22, and is connected to the anode side of a thyristor SCR2.

Subsequent circuit blocks L₂, L₃ . . . L₆ associated with subsequent pilot lamps and storage circuits are the same as the above-described circuit block, except that the last circuit block containing a thyristor SCR6 is not connected to a subsequent circuit block. The subsequent circuit blocks contain corresponding elements switches SW_{a1}, SW_{a2} . . . SW_{a6} thyristors SCR2 . . . SCR6, and so on.

When a sheet of paper is first delivered from the hopper, the changeover switch SW_{S1} is actuated to connect the terminal of the resistor R_{b1} with the terminal of the capacitor C_{b1}, the thyristor SCR1 is fired and conducts, and the pilot lamp 21 lights up. Conduction of the thyristor SCR1 causes the base voltage of the NPN transistor Ta1 to be lowered, and the transistor Ta1 is cut off. When the transistor Ta1 is cut off, its collector voltage rises, and capacitor C_{c1} begins to be charged. The time required for the capacitor C_{c1} to be charged to its final voltage is set by suitable adjustment of the variable resistor VR_{a1}, and is made slightly longer than the time required for a sheet of paper to travel from the hopper outlet to the detector 1.

At the moment the sheet of paper reaches the detector 1, the changeover switch SW_{a1} is actuated to connect the terminal of the resistor R_{b2} with the terminal of the capacitor C_{b2}. The thyristor SCR2 is therefore fired and conducts. Conduction of the thyristor SCR2 causes the pilot lamp 22 to light up. Also, because of the capacitor C_{a1}, when the thyristor SCR2 conducts, the anode voltage of the thyristor SCR1 drops, and thyristor SCR1 is cut off. When SCR1 is cut off, the base voltage of the NPN transistor Ta1 rises, and transistor Ta1 conducts. When transistor Ta1 conducts, its collector voltage drops, and the previously charged capacitor C_{c1} discharges. Thyristor SCR1 therefore does not conduct until the next gate input thereto, provided when the next sheet of paper is fed from the hopper and the changeover switch SW_{S1} is actuated again, and the pilot lamp 21 is switched off.

If another sheet of paper is fed from the hopper, and the thyristor SCR1 is fired again while the thyristor SCR2 is still conducting, the capacitor C_{a1} is charged, in the reverse direction to that described above, through resistor R_{h1}, and the thyristor SCR2 is unaffected.

The above-described circuit action is repeated in successive circuit blocks L₂, L₃ . . . L₆, as copy-paper is transported through the photocopying machine, comes to successive detectors, and actuates successive switches SW_{a2} . . . SW_{a6}. When the paper passes the switch SW_{a6}, and comes to the last detector 6, the thyristor SCR6 is simply cut off, and no further circuit ac-

tion takes place, thus completing one photocopying cycle.

In FIG. 5, there is shown a circuit diagram of control circuit blocks similar to those of FIG. 4 according to another embodiment of the invention.

The same circuit blocks are provided in association with each pilot lamp and timer. The description will therefore proceed with reference to the first circuit block, it being understood that the other circuit blocks are the same.

Referring to FIG. 5, the first circuit block N may be seen to include a normally open switch SWs2. One side of the switch is connected to a resistor RK1. This resistor is, in turn, coupled to the base of PNP transistor Tb1 and to a resistor Rj1. Resistor Rj1 is connected to a variable resistor VRa1, to the emitter of the transistor Tb1 and to one side of a resistor Rr1. The other side of the resistor Rr1 is coupled to the cathode side of a diode DF1 and to one side of the pilot lamp 21.

The other side of the switch SWs2 is connected to a capacitor Cd1; to the emitter of an NPN transistor TC1; to the emitter of an NPN transistor Td1 and to the base of the transistor through resistor Rt1; and to the other side of the lamp 21. The resistor Rt1 is connected to the collector of PNP transistor Tb1 through serially coupled resistors Rs1 and Rg1. The capacitor Cd1 is in series with a diode Dd1 and an output terminal 01, which is connected with the timer 32, the output terminal 01 being on the cathode side of the diode Dd1. The anode side of the diode Dd1, and the resistor Rml are connected in series with the collector of the transistor Tc1, and in parallel to one another. The base of the transistor Tc1 is connected to the collector of the transistor Td1, through a diode De1, and to the base of the transistor Tb1, through the diode De1 and resistor Rp1, the transistor Tc1 being on the anode side of the diode De1. The base of the transistor Td1 is connected to the anode side of the diode Df1 and also to the anode side of a diode Dg1. The anode side of the diode Df1 is also connected to the collector of the transistor Tb1. The cathode side of the diode Dg1 is connected to one side of a normally open contact SWb1, which closes a circuit associated with the pilot lamp 22.

When a sheet of copy-paper is fed from the hopper 103, the normally open switch SWs2 is closed, the base voltage of the PNP transistor Tb1 drops, and transistor Tb1 conducts. Current from the transistor Tb1 is passed through diode Df1, and is supplied to and lights up lamp 21. At the same time a voltage is applied to the base of the NPN transistor Td1, and so transistor Td1 also conducts. The base current of the transistor Tb1 flows also through the transistor Td1, and so even after the contact SWs2 is opened, transistors Tb1, Td1 continue to conduct. The NPN transistor Tc1 conducts prior to closure of the contact SWs2, but conduction of transistor Td1 lowers the transistor Tc1 base voltage and cuts off the transistor Tc1. The collector voltage of transistor Tc1 therefore rises, and capacitor Cd1 is charged.

When the sheet of paper reaches detector 1, contact SWb1 is closed, and transistors Tb2, Td2 conduct. At the same time NPN transistor Td1 base voltage is lowered, and transistor Td1 is cut off. When transistor Td1 is cut off, base current of transistor Tb1 also stops, transistor Tb1 is cut off, and the lamp 21 is turned off, the first circuit block N1 thus returning to its original condition.

In the case where there is a stoppage, and contact SWb1 is not closed, suitable adjustment of the variable resistor VRa1 keeps the transistor Tc1 cut off, and after a certain time, when the charge on the capacitor Cd1 has reached a certain value, a signal indicating that there is a stoppage is supplied to the output terminal 01.

In the circuit shown in FIG. 5, the state of each circuit block has no effect on the action of the succeeding 10 circuit block N2, N3 . . . N6, and there are therefore no restrictions concerning the minimum distance between detectors.

In other words, if the distance between the detectors 1, 2, as shown in FIG. 2, is shorter than a sheet of copy-paper, and both detectors 1, 2 are simultaneously actuated by a single sheet, the only result is that the pilot lamps 21, 22 are both on at the same time, and circuit operation for stoppage warning purposes is not affected. However, in the employment of cascade-15 connected circuits as shown in FIG. 5, if the distance between two detectors, for example, detectors 1, 2 is such that both may be actuated simultaneously by a single sheet of copy-paper, in order to keep the related storage circuits set for a suitable time, the variable resistors should be adjusted so as to make the set time of 20 the corresponding timers equal to the standard time required for the passage of a sheet of paper plus an additional allowance.

Some photocopying machines may employ copy-30 paper sheets of different sizes, sheets of one size being large enough to actuate two detectors simultaneously, and sheets of another size actuating only one detector at a time. To effect rapid indication of a paper feed 35 stoppage in such photocopying machines, the circuits are adjusted to keep the switches SWb1, SWb2 . . . SWb6 closed only for the length of time necessary to keep the storage circuits set during the passage of sheets.

FIG. 6, shows a circuit, in which the detector contact 40 switches SWb1, SWb2 . . . SWb6 are made no-contact switches. The circuit may be seen to be similar to that shown in FIG. 5, except for a detector circuit M, which is surrounded by a one dot chain line. The detector circuit M, may be seen to comprise a photoconductive cell CdS1, PNP transistor Te1, NPN transistor Tf1, and zener diode Zd1. The base of the transistor Te1 is connected to the photoconductive cell CdS1, the emitter thereof is connected to the anode side of the zener diode Zd1, and the collector thereof is connected to the base of the transistor Tf1 through resistor RY1. On one side, the normally open contact SWs3 is connected to the photosensitive cell CdS1 and to the cathode side of the zener diode Zd1 through a pair of serially connected resistors RK1 and RJ1. On the other side, the contact SWs3 is connected to the other side of the photosensitive cell CdS1 through resistors VRc1 and Rx1, to the base and to the collector of the transistor Te1 through various resistors, and to the emitter of the transistor Tf1.

In the photocopying machine, a small lamp (not shown), or similar light source, is positioned opposite the photosensitive cell CdS1. The small lamp normally illuminates the cell CdS1. In this case, the resistance of the cell CdS1 is low, and the PNP transistor Te1 is cut off. Transistor Te1 being cut off, the NPN transistor Tf1 also is cut off. When a sheet of paper comes between the small lamp and cell CdS1, illumination of the

cell CdS1 is cut, and the resistance thereof rises to a high value. Therefore, the base voltage of the PNP transistor Te1 falls, base current flows, and transistors Te1, Tf1 conduct. This has the same result as the closure of the switch SWb1 in FIG. 5, and the pilot lamp 21 is switched on.

In the circuits of FIGS. 4, 5, 6, the output terminals 01, 02 . . . 06 are connected to the input of the OR gate shown in FIGS. 2, 3.

As is clear from the above description, the present invention provides a paper feed stoppage detection means for electronic photocopying machines, which gives an immediate warning upon the occurrence of a stoppage, and also gives an indication of the location of the stoppage, and is thus of great advantage in the operation of photocopying machines. Also, the means of the invention is compact in construction, since it is necessary to provide only a single warning device, which is actuated when there is a stoppage at any location. Timers employed in the means of the invention may be set to fixed times, and do not need to be adjusted in correspondence to changes in a photocopying process, and a circuit of the same structure may be used in association with each detector. The means of the invention is thus cheap, reliable, and maintenance thereof is easy. Lamps are provided to give an immediate indication of the locations of sheets of copy-paper, thereby making supervision of the copying machine easy. Also, the means of the invention accurately detects stoppages, even if sheets are fed through a machine at different intervals.

Needless to say, the detection means according to the present invention is not limited to detection of stoppage in the feed of paper through a photocopying machine, but may be employed for the detection of stoppage of any other articles carried over a set path.

Although the present invention has been fully disclosed by way of the preferred embodiment thereof shown in the accompanying drawings, it is to be noted that various changes and modifications, including those mentioned in the foregoing description, are apparent to those skilled in the art. Therefore, unless otherwise such changes and modifications depart from the true scope of the present invention, they should be construed as included therein.

What is claimed is:

1. A paper jam detecting means for use in an electro-photographic copying machine and the like, comprising:

a plurality of detectors located at various points along the path of travel of a sheet of copying paper through said machine, each of said detectors producing an output signal upon detection of passage of a sheet of copying paper;

a plurality of storage circuits, each having set and reset states and producing an output signal only when in the set state, a first of said plurality of storage circuits being set by an input signal supplied thereto at the start of feed of a sheet of copying paper, a first of said plurality of detectors operatively coupled thereto, whereby said first storage circuit is reset by the output of said first detector, a second of said plurality of storage circuits operatively coupled to a detector located at the entrance to an exposure chamber and adapted to be reset by an input signal generated upon the commencement of exposure of a sheet of copying paper, a third of said

plurality of storage circuits operatively coupled to a detector located at the exit of the exposure chamber and adapted to be set by a signal generated upon completion of exposure of the sheet of copying paper, the remaining ones of said plurality of storage circuits each operatively coupled to two successive detectors, one detector setting said storage circuit, thereby producing an output signal, the second detector resetting said storage circuit thereof;

a plurality of timers, each coupled to one of said storage circuits and activated by the output thereof, each of said timers producing an output if actuated for more than a predetermined time; and alarm means coupled to all of said timers and adapted to be actuated by an output signal of any one of said timers.

2. A paper jam detection means as claimed in claim 1, further comprising a plurality of indicating means each associated with a respective one of said storage circuits, said indicating means adapted to be energized when a corresponding storage circuit is set and to be deenergized when reset, whereby indication is provided of an exact position where jamming has occurred.

3. A paper jam detection means in an electrophotographic copying machine and the like, comprising:

a plurality of detectors provided on a feed path of copying papers through said machine, at least one of said detectors located at the entrance of an exposure chamber and a second detector located at the exit of the exposure chamber, each of said detectors adapted to sense the arrival of a sheet of copying paper and producing an output responsive thereto;

a plurality of storage circuits associated with said detectors;

a plurality of timers, each associated with a respective one of said storage circuits, one of said storage circuits coupled to said detector located at the entrance of the exposure chamber and adapted to be set by a signal from said detector to actuate the associated timer and adapted to be reset by a signal indicating the commencement of exposure, another of said storage circuits coupled to the detector located at the exit of the exposure chamber and adapted to be set by a signal indicating the completion of exposure to actuate the associated timer and adapted to be reset by a signal from said detector; and

a warning means coupled to each of said timers, said means being actuated with any of said storage circuits fails to be reset within a time set by said timers.

4. A paper jam detection means as claimed in claim 3 wherein each of said storage circuits includes a set input terminal, a reset input terminal and a first output terminal, whereby each storage circuit may be set by the application of a signal to the set input terminal to actuate a corresponding one of the timers through the output terminal and whereby the circuit may be reset by the application of a signal to the reset input terminal.

5. A paper jam detection means as claimed in claim 4, wherein each of said storage circuits further includes a second output terminal connected to a lamp, said lamp being energized when said circuit is set and deenergized when said circuit is reset.

6. A paper jam detection means as claimed in claim 3 wherein the setting time for the timer associated with the storage circuit corresponding to the detector located at the entrance of the exposure chamber is determined by $T_1 = (l_1/S_1) + \alpha_1$ wherein T_1 is the setting time, l_1 is the distance from said detector to the exposure position, S_1 is the traveling speed of a copying paper over said distance l_1 and α_1 is a suitable time allowance and wherein the setting time for the timer as-

sociated with the storage circuit corresponding to the detector located at the exit of the exposure chamber and is determined by $T_2 = (l_2/S_2) + \alpha_2$ wherein T_2 is the setting time, l_2 is the distance from the exposure position to said detector, S_2 is the travelling speed of a copying paper for said distance l_2 and α_2 is a suitable time allowance.
